ELASTIC LACE SLIPPER

Gustave Cohn, New York, N. Y.

Application December 14, 1949, Serial No. 6,601

Term of patent 3½ years

(Cl. D7—7)

To all whom it may concern:

Be it known that I, Gustave Cohn, a citizen of the United States, residing in the Borough of Manhattan, city and State of New York, have invented a new, original, and ornamental Design for an Elastic Lace Slipper, of which the following is a specification, reference being had to the accompanying drawing, forming part thereof, in which:

Fig. 1 is a top perspective view of an elastic lace slipper, showing my new design; and

Fig. 2 is a side elevational view of Fig. 1.

I claim:

The ornamental design for an elastic lace slipper, substantially as shown.

GUSTAVE COHN.
